FOLDING TABLE

Edward R. Jaysane, Bronxville, N. Y., assignor of one-half to Robert Calvert, New York, N. Y.

Application August 25, 1954, Serial No. 452,178

8 Claims. (Cl. 273—30)

This invention relates to a folding table.

The table is adapted for use as a serving table, picnic table, or for games of various kinds. It is particularly useful for table tennis (ping pong) and will be first illustrated in connection with such use.

Briefly stated, the invention comprises a table including the following features alone or in combination: means for causing a handle of the table to be exposed when the table is in folded condition and to be withdrawn and concealed below the top surface when the table is opened to position for use; means associated with the handle for holding the folded parts of the table together when a lifting force is applied to the handle; a central leg unit extending below the line of meeting of the parts of the top when the table is in open position; means establishing the said central leg unit at approximately a right angle to the table top in open position; and, in the table tennis embodiment of the invention, means associated with the central leg unit for supporting a net across and above the top of the table.

The invention will be described in connection with the attached drawings to which reference is made.

Fig. 1 is a view partly in section of the table tennis embodiment of the table in folded or closed position.

Fig. 2 is a sectional view on line 2—2 of Fig. 1.

Fig. 3 is a view partly in section of the table in partly opened condition.

Fig. 4 is a view partly in section of the table in completely unfolded condition, ready for use.

Fig. 5 is a similar view on an enlarged scale of the midportion of the table in open position.

Fig. 6 is a view partly in section on line 6—6 of Fig. 4 showing the table with a playing net supported above the level of the top thereof.

There is shown a folding table with a plurality of top parts 10 and 12 with hinge 14 securing the parts to each other at the meeting edges thereof, so that, when the top is folded, the backs of the top move towards each other. The handle 16 is secured to flexible spring strip 18 as by a friction fit within the slot in handle 16 (Fig. 5). The ends of the flexible strip are secured by fastening elements 20 such as bolts, screws, or rivets to rigid strut members 22 and 24 which at their other ends are connected, as in hingewise manner by part 26, to the table legs 28 through the bar 30.

The table contains also a central leg unit extending in the opened table below the line of hinging of the parts of the table top and including legs 33, a bar 34 connecting the two legs 33 and establishing them in fixed relationship to each other, hinge members 36, one at each side connecting the bar 34 to the underside of the table top or, more strictly, to reenforcing frame 38 forming a part of the table top and defining therewithin spaces to receive the legs when the table is in folded position.

The central leg unit contains also a sliding post support 40 to receive the rod 42 extending into block 44. Block 44 is provided with hole to receive the pin 46 for supporting the playing net 48, as by being tied at positions 50 around the upper part of the said pin.

The central leg unit on one side is connected by the

2

hinge 52 to the frame constituting a part of the top of the table and on the other side to the frame by a short metal strip 54 provided with slot 56 in which is engaged stop 58, the stop 58 at one end being anchored in the leg 33.

5 The length of this strip is such that when the table is opened as shown in Fig. 4 the stop member holds the strip in taut position and the strip prevents movement of the central leg unit in direction away from the said strip.

The frame 38 is disposed at a distance, from the place 10 of hinging of legs 28 to the table top 10 (Fig. 3), that is equal approximately to the thickness of the legs as shown at 60. As a result, the frame provides a stop against the outward movement of the legs 28 to a position beyond a right angle to the plane of the top of the table.

15 The materials of construction may be those that are conventional in like parts of other apparatus of this type. Thus the hinges may be of metal. The flexible springy strip 18 may be constructed of strip spring steel, stainless steel, or the like. The table top, the apron that extends 20 as a frame below the table top, and the legs, bars and strut members are suitably of wood, plastic or metal. I have used to advantage plywood of mahogany or walnut surface for the upper parts 10 and 12 of the top and mahogany, redwood, fir, or soft pine for the frame 38, legs 28 and 33, and the various bars and struts.

25 The operation of the table will be largely evident from the description of it that has already been given.

The table is opened by unfolding the parts 10 and 12 along the line of hinging of them and moving the legs 30 28 to positions at right angles to the table top. This causes tightening of flexible strip 18, and decreasing of the angle of upward bowing of it, orientation of legs 33 below the line of folding, and withdrawal of the handle 16, to within the space formed by slots 17 and 19 in 35 registering areas of the meeting edges of parts 10 and 12 and below the upper surface thereof. As a result the handle is concealed below the table top, as illustrated particularly in Fig. 5.

30 As the table is thus unfolded, the legs 28, on their outer sides and near the positions of hinging of the legs to the table top, strike shoulders on the frame 38. Further movement of the legs outwardly is thus prevented. Also, the handle being locked in the space defined by the slots 17 and 19 fixes the level of the uppermost part of the 35 flexible strip 18, within the handle, so that the spring then restricts or permits entirely any movement of the leg 32 in inward manner.

35 The hinge 52 on the central leg unit with leg 33 and the spring strip 54 bring the said unit into position, when the table is opened, directly below and at right angles to the line of hinging of the top parts 10 and 12 of the table (Figs. 3 and 5).

40 When the table is to be used for tennis table, then the pins 42 are inserted in the slots 40 so that the parts attached to the pin 42 support the playing net at the proper level transversely with respect to the length of the table and above the middle thereof. Also the table top may be provided with lines (not shown) to outline the different areas of the playing surface for the game.

45 The bowed strip 18 extends movably through slots in the meeting edges of the table top parts 10 and 12 and then laterally in opposite directions.

50 When the table is in closed position, there is defined between the backs of the parts 10 and 12 a space to receive not only the legs which come within the space when the table is folded but also attachments of conventional nature (not shown) to receive and hold the playing paddles when not in use or tableware and utensils when the device is to be used as a picnic table.

55 It will be understood that it is intended to cover all changes and modifications of the examples of the invention herein chosen for the purpose of illustration which

do not constitute departures from the spirit and scope of the invention.

What I claim is:

1. In a folding table including a handle that is exposed when the table is folded, a top with a plurality of hinged parts, and legs hinged to the top and foldable thereunder, the improvement comprising means attaching the handle to the legs, so that the handle is withdrawn in the direction of the table top as the legs are moved to the positions for supporting the table, and means for holding the handle in established position in the unfolded table.

2. In a folding table including a handle that is exposed when the table is folded, a top with a plurality of hinged parts, and legs hinged to the top and foldable thereunder, the improvement comprising an upwardly bowed spring metal strip extending from the handle, movably through adjacent edges of the hinged parts of the table tops, and then laterally in opposite directions beneath the table top, a portion of the handle engaging the upper part of the strip, and means securing the strip, on each side of the handle and below the level thereof in the upright table, to the legs, so that movement of the legs outwardly decreases the angle of curvature of the bowed strip and exerts a downward force on the handle.

3. A table as described in claim 1 in which the means for moving the legs to the supporting position include spring metal strips, a portion of the handle engaging the said strips, strut elements, fastening means securing each of the said strips to a strut at a position remote from the handle, and means connecting another part of each strut in hinged manner to a leg of the table, so that movement of the legs causes movement of the struts, flexible strips, and the handle.

4. A table as described in claim 1 including a central leg unit adapted to extend downward below and parallel to the line of hinging of the hinged parts of the table top, a hinge member securing the said leg unit to one of the said parts of the top, and a slotted strip member securing the central leg unit movably to the adjacent one of the parts of the table top, a stop element slidably engaged within the slot of the slotted member and also an-

chored in the leg unit, the slotted member being of length to be held tight by the said stop when the central leg unit is in the supporting position below the line of hinging of the parts of the table top.

5. A table as described in claim 4, the said central leg unit including two spaced legs and a cross member securing the spaced legs in fixed relationship to each other, supports for holding a playing net above the table top, and means for holding the said supports on the central leg unit.

10 6. A folding table comprising a handle, hinged legs, and a top in the form of a pair of hinged parts with meeting edges, registering parts of the meeting edges provided with slots defining, in the opened table, a space 15 to receive and conceal the handle, and means for moving the handle to the said space by movement of the legs to the position for supporting the table.

20 7. A table including legs mounted in hinged manner so as to be foldable under the table, a handle, and flexible unions between the handle and the said legs at positions below the hinging of the legs to the table top, so that raising the handle above the table top causes movement of the legs to the folded-under position and force applied to the legs, moving them to the unfolded 25 position, causes lowering of the handle.

8. A table as described in claim 1 including a frame 30 extending around and below the upper parts of the top and forming within the frame shoulders disposed at distances, from the positions of hinging of the legs, equal to the thicknesses of the said legs and on the sides thereof opposite the hinges, so that, when the legs are moved to the supporting positions at a right angle to the top of the table, the frame forms stops against further outward movement of the legs.
